US00D543583S

(12) **United States Design Patent** (10) **Patent No.:** **US D543,583 S**
Workman et al. (45) **Date of Patent:** **** May 29, 2007**

(54) **ELECTRONIC CUTTER**

(75) Inventors: **Robert Workman**, Mapleton, UT (US); **Desiree Tanner**, San Clemente, CA (US); **William Craig Youse**, Provo, UT (US); **Jason B. Brinkerhoff**, Lindon, UT (US); **Jonathan Aaron Johnson**, Orem, UT (US); **Michael Horito**, Provo, UT (US); **Gerry Ayala**, Provo, UT (US); **Ken Yan**, Shenzhen (CN)

(73) Assignee: **Provo Craft and Novelty, Inc.**, Spanish Fork, UT (US)

(**) Term: **14 Years**

(21) Appl. No.: **29/234,211**

(22) Filed: **Jul. 14, 2005**

(51) **LOC (8) Cl. 18-04**

(52) **U.S. Cl. D18/34.3**

(58) **Field of Classification Search** D18/34.1-34.9, D18/99, 54, 50; 83/167, 289, 302, 203, 523, 83/633; 241/169.1, 36, 154, 157, 222, 224, 241/168, 284, 295, 37.5, 285.1, 285.2, 100, 241/236; D8/99, 105; D7/381, 383; D14/356; D13/83; D19/65, 72

(57) **CLAIM**

The ornamental design for an electronic cutter, as shown and described.

DESCRIPTION

FIG. 1 is a top and front perspective view of an electronic cutter showing our new design;

FIG. 2 is a front elevation thereof;

FIG. 3 is a rear elevation thereof;

FIG. 4 is a top plan view thereof;

FIG. 5 is a bottom plan view thereof;

FIG. 6 is a right side elevation thereof; and,

FIG. 7 is a left side elevation thereof.

The broken line showing of environment in the figure drawings is for illustrative purposes only and forms no part of the claimed design.
